RAYMOND F. JAHN, OF BROOKLYN, NEW YORK

PRINTING AND STAMPING MACHINE

Original application filed April 13, 1927, Serial No. 183,318, Patent No. 1,744,770, dated January 28, 1930.
 Divided and this application filed June 22, 1929. Serial No. 372,823.

This is a division of original application filed by me April 13, 1927, Serial No. 183,318.

This invention relates to improvements in printing and stamping machines, and has 5 particular reference to such devices which are adapted for endorsing, cancelling, or otherwise printing upon bank checks, tickets, letters, and similar articles.

The subject matter of this invention is dis- 10 closed in my co-pending application for Printing and stamping machines, filed April 13, 1927, Serial No. 183,318 but is not claimed therein, the present application being a division of the said application Serial No. 183,318.

15 In the above identified co-pending application, the invention has been embodied in a machine which is power-driven and capable of expeditiously operating upon a quantity of successively fed paper sheets or like articles as they are passed through a printing couple. This printing couple comprises an impression roller and a printing roller rotat- 20 ing in opposition to each other, and the prin- cipal object of this invention is to provide a 25 novel inking mechanism for supplying ink to the printing roller. A supply of ink is main- tained in an ink well which is mounted on a pair of swinging arms and provided with an ink roller and a wiping roller. The arms 30 which support the ink well are eccentrically pivoted to another pair of arms, which in turn are pivoted to the main frame or base 35 of the machine, and the last-mentioned arms carry a distributing roller which mutually 40 engages the ink roller and the printing roller. Thus the ink roller and the distributing roller are normally held yieldingly against the printing roller, and a suitable latch is pro- vided for rendering the inking mechanism inactive when desired.

The foregoing and other objects, features, and advantages of the invention will be readily understood from the following description in connection with the accompanying drawings, wherein one form of the invention has been shown by way of illustration, and wherein

Fig. 1 is a top plan view of the improved 50 printing machine; and

Fig. 2 is a fragmentary vertical sectional view on line 2—2 of Fig. 1.

The invention has been shown as embodied in a machine for endorsing bank checks, and in the following description, when bank checks are specified in connection with the operation of the device, it is to be understood that their equivalents may be operated upon in the same way. The device comprises a sub- 5 stantially flat base plate A¹, here shown as of rectangular outline and preferably having a plurality of cushion feet whereby to be supported upon a desk, table, or the like without likelihood of damaging the surface thereof. Secured to the base plate A¹ intermediate its 10 ends is a supporting bracket A³ having a pair of upwardly extending spaced arms A⁴ and A⁵, said arms being disposed adjacent the opposite side edges of the base plate. Adjacent their upper ends, the arms A⁴ and A⁵ are provided with bearing bosses having axially alined openings in which are secured 15 stationary mounting shafts, the inner ends of which are spaced from each other to rotatably support a novel printing roller B of the 20 printing couple. While this printing roller may be of any desired form, I prefer to make use of one of the type disclosed and claimed 25 in said application Serial No. 183,318.

An impression roller B⁴⁵ is journaled for 30 rotation above the printing roller B, and power is supplied by an electric motor C¹¹ to rotate the said printing and impression rollers through suitable gearing and clutch mechanism, not shown, and successive rota- 35 tions of the printing roller are controlled by the tripping mechanism D as it is acted upon by the successively fed checks.

The novel inking mechanism of this in- 40 vention is best illustrated in Fig. 2 and com- prises an ink well F¹, provided at its oppo- 45 site ends with arms F², which are pivotally attached to swinging arms F³ by means of pins F⁴. The arms F³ are pivotally sup- 50 ported on a stationary rod F⁵ which extends 55 longitudinally between the stationary arms A⁵ and A⁶, the pins F⁴ being eccentrically disposed with reference to said rod F⁵, and each of the arms F² has secured to its outer 60 end one end of a tension spring F⁶, the other 65 end of which is secured to the base plate A¹. The arms F² are pivotally supported on the rod F⁵ by means of pins F⁷, and the arms F³ are pivotally supported on the arms F² by means of pins F⁸. The arms F³ are pivotally supported on the rod F⁵ by means of pins F⁹, and the arms F² are pivotally supported on the base plate A¹ by means of pins F¹⁰. The arms F² are pivotally supported on the rod F⁵ by means of pins F¹¹, and the arms F³ are pivotally supported on the arms F² by means of pins F¹². The arms F³ are pivotally supported on the rod F⁵ by means of pins F¹³, and the arms F² are pivotally supported on the base plate A¹ by means of pins F¹⁴. The arms F² are pivotally supported on the rod F⁵ by means of pins F¹⁵, and the arms F³ are pivotally supported on the arms F² by means of pins F¹⁶. The arms F³ are pivotally supported on the rod F⁵ by means of pins F¹⁷, and the arms F² are pivotally supported on the base plate A¹ by means of pins F¹⁸. The arms F² are pivotally supported on the rod F⁵ by means of pins F¹⁹, and the arms F³ are pivotally supported on the arms F² by means of pins F²⁰. The arms F³ are pivotally supported on the rod F⁵ by means of pins F²¹, and the arms F² are pivotally supported on the base plate A¹ by means of pins F²². The arms F² are pivotally supported on the rod F⁵ by means of pins F²³, and the arms F³ are pivotally supported on the arms F² by means of pins F²⁴. The arms F³ are pivotally supported on the rod F⁵ by means of pins F²⁵, and the arms F² are pivotally supported on the base plate A¹ by means of pins F²⁶. The arms F² are pivotally supported on the rod F⁵ by means of pins F²⁷, and the arms F³ are pivotally supported on the arms F² by means of pins F²⁸. The arms F³ are pivotally supported on the rod F⁵ by means of pins F²⁹, and the arms F² are pivotally supported on the base plate A¹ by means of pins F³⁰. The arms F² are pivotally supported on the rod F⁵ by means of pins F³¹, and the arms F³ are pivotally supported on the arms F² by means of pins F³². The arms F³ are pivotally supported on the rod F⁵ by means of pins F³³, and the arms F² are pivotally supported on the base plate A¹ by means of pins F³⁴. The arms F² are pivotally supported on the rod F⁵ by means of pins F³⁵, and the arms F³ are pivotally supported on the arms F² by means of pins F³⁶. The arms F³ are pivotally supported on the rod F⁵ by means of pins F³⁷, and the arms F² are pivotally supported on the base plate A¹ by means of pins F³⁸. The arms F² are pivotally supported on the rod F⁵ by means of pins F³⁹, and the arms F³ are pivotally supported on the arms F² by means of pins F⁴⁰. The arms F³ are pivotally supported on the rod F⁵ by means of pins F⁴¹, and the arms F² are pivotally supported on the base plate A¹ by means of pins F⁴². The arms F² are pivotally supported on the rod F⁵ by means of pins F⁴³, and the arms F³ are pivotally supported on the arms F² by means of pins F⁴⁴. The arms F³ are pivotally supported on the rod F⁵ by means of pins F⁴⁵, and the arms F² are pivotally supported on the base plate A¹ by means of pins F⁴⁶. The arms F² are pivotally supported on the rod F⁵ by means of pins F⁴⁷, and the arms F³ are pivotally supported on the arms F² by means of pins F⁴⁸. The arms F³ are pivotally supported on the rod F⁵ by means of pins F⁴⁹, and the arms F² are pivotally supported on the base plate A¹ by means of pins F⁵⁰. The arms F² are pivotally supported on the rod F⁵ by means of pins F⁵¹, and the arms F³ are pivotally supported on the arms F² by means of pins F⁵². The arms F³ are pivotally supported on the rod F⁵ by means of pins F⁵³, and the arms F² are pivotally supported on the base plate A¹ by means of pins F⁵⁴. The arms F² are pivotally supported on the rod F⁵ by means of pins F⁵⁵, and the arms F³ are pivotally supported on the arms F² by means of pins F⁵⁶. The arms F³ are pivotally supported on the rod F⁵ by means of pins F⁵⁷, and the arms F² are pivotally supported on the base plate A¹ by means of pins F⁵⁸. The arms F² are pivotally supported on the rod F⁵ by means of pins F⁵⁹, and the arms F³ are pivotally supported on the arms F² by means of pins F⁶⁰. The arms F³ are pivotally supported on the rod F⁵ by means of pins F⁶¹, and the arms F² are pivotally supported on the base plate A¹ by means of pins F⁶². The arms F² are pivotally supported on the rod F⁵ by means of pins F⁶³, and the arms F³ are pivotally supported on the arms F² by means of pins F⁶⁴. The arms F³ are pivotally supported on the rod F⁵ by means of pins F⁶⁵, and the arms F² are pivotally supported on the base plate A¹ by means of pins F⁶⁶. The arms F² are pivotally supported on the rod F⁵ by means of pins F⁶⁷, and the arms F³ are pivotally supported on the arms F² by means of pins F⁶⁸. The arms F³ are pivotally supported on the rod F⁵ by means of pins F⁶⁹, and the arms F² are pivotally supported on the base plate A¹ by means of pins F⁷⁰. The arms F² are pivotally supported on the rod F⁵ by means of pins F⁷¹, and the arms F³ are pivotally supported on the arms F² by means of pins F⁷². The arms F³ are pivotally supported on the rod F⁵ by means of pins F⁷³, and the arms F² are pivotally supported on the base plate A¹ by means of pins F⁷⁴. The arms F² are pivotally supported on the rod F⁵ by means of pins F⁷⁵, and the arms F³ are pivotally supported on the arms F² by means of pins F⁷⁶. The arms F³ are pivotally supported on the rod F⁵ by means of pins F⁷⁷, and the arms F² are pivotally supported on the base plate A¹ by means of pins F⁷⁸. The arms F² are pivotally supported on the rod F⁵ by means of pins F⁷⁹, and the arms F³ are pivotally supported on the arms F² by means of pins F⁸⁰. The arms F³ are pivotally supported on the rod F⁵ by means of pins F⁸¹, and the arms F² are pivotally supported on the base plate A¹ by means of pins F⁸². The arms F² are pivotally supported on the rod F⁵ by means of pins F⁸³, and the arms F³ are pivotally supported on the arms F² by means of pins F⁸⁴. The arms F³ are pivotally supported on the rod F⁵ by means of pins F⁸⁵, and the arms F² are pivotally supported on the base plate A¹ by means of pins F⁸⁶. The arms F² are pivotally supported on the rod F⁵ by means of pins F⁸⁷, and the arms F³ are pivotally supported on the arms F² by means of pins F⁸⁸. The arms F³ are pivotally supported on the rod F⁵ by means of pins F⁸⁹, and the arms F² are pivotally supported on the base plate A¹ by means of pins F⁹⁰. The arms F² are pivotally supported on the rod F⁵ by means of pins F⁹¹, and the arms F³ are pivotally supported on the arms F² by means of pins F⁹². The arms F³ are pivotally supported on the rod F⁵ by means of pins F⁹³, and the arms F² are pivotally supported on the base plate A¹ by means of pins F⁹⁴. The arms F² are pivotally supported on the rod F⁵ by means of pins F⁹⁵, and the arms F³ are pivotally supported on the arms F² by means of pins F⁹⁶. The arms F³ are pivotally supported on the rod F⁵ by means of pins F⁹⁷, and the arms F² are pivotally supported on the base plate A¹ by means of pins F⁹⁸. The arms F² are pivotally supported on the rod F⁵ by means of pins F⁹⁹, and the arms F³ are pivotally supported on the arms F² by means of pins F¹⁰⁰. The arms F³ are pivotally supported on the rod F⁵ by means of pins F¹⁰¹, and the arms F² are pivotally supported on the base plate A¹ by means of pins F¹⁰². The arms F² are pivotally supported on the rod F⁵ by means of pins F¹⁰³, and the arms F³ are pivotally supported on the arms F² by means of pins F¹⁰⁴. The arms F³ are pivotally supported on the rod F⁵ by means of pins F¹⁰⁵, and the arms F² are pivotally supported on the base plate A¹ by means of pins F¹⁰⁶. The arms F² are pivotally supported on the rod F⁵ by means of pins F¹⁰⁷, and the arms F³ are pivotally supported on the arms F² by means of pins F¹⁰⁸. The arms F³ are pivotally supported on the rod F⁵ by means of pins F¹⁰⁹, and the arms F² are pivotally supported on the base plate A¹ by means of pins F¹¹⁰. The arms F² are pivotally supported on the rod F⁵ by means of pins F¹¹¹, and the arms F³ are pivotally supported on the arms F² by means of pins F¹¹². The arms F³ are pivotally supported on the rod F⁵ by means of pins F¹¹³, and the arms F² are pivotally supported on the base plate A¹ by means of pins F¹¹⁴. The arms F² are pivotally supported on the rod F⁵ by means of pins F¹¹⁵, and the arms F³ are pivotally supported on the arms F² by means of pins F¹¹⁶. The arms F³ are pivotally supported on the rod F⁵ by means of pins F¹¹⁷, and the arms F² are pivotally supported on the base plate A¹ by means of pins F¹¹⁸. The arms F² are pivotally supported on the rod F⁵ by means of pins F¹¹⁹, and the arms F³ are pivotally supported on the arms F² by means of pins F¹²⁰. The arms F³ are pivotally supported on the rod F⁵ by means of pins F¹²¹, and the arms F² are pivotally supported on the base plate A¹ by means of pins F¹²². The arms F² are pivotally supported on the rod F⁵ by means of pins F¹²³, and the arms F³ are pivotally supported on the arms F² by means of pins F¹²⁴. The arms F³ are pivotally supported on the rod F⁵ by means of pins F¹²⁵, and the arms F² are pivotally supported on the base plate A¹ by means of pins F¹²⁶. The arms F² are pivotally supported on the rod F⁵ by means of pins F¹²⁷, and the arms F³ are pivotally supported on the arms F² by means of pins F¹²⁸. The arms F³ are pivotally supported on the rod F⁵ by means of pins F¹²⁹, and the arms F² are pivotally supported on the base plate A¹ by means of pins F¹³⁰. The arms F² are pivotally supported on the rod F⁵ by means of pins F¹³¹, and the arms F³ are pivotally supported on the arms F² by means of pins F¹³². The arms F³ are pivotally supported on the rod F⁵ by means of pins F¹³³, and the arms F² are pivotally supported on the base plate A¹ by means of pins F¹³⁴. The arms F² are pivotally supported on the rod F⁵ by means of pins F¹³⁵, and the arms F³ are pivotally supported on the arms F² by means of pins F¹³⁶. The arms F³ are pivotally supported on the rod F⁵ by means of pins F¹³⁷, and the arms F² are pivotally supported on the base plate A¹ by means of pins F¹³⁸. The arms F² are pivotally supported on the rod F⁵ by means of pins F¹³⁹, and the arms F³ are pivotally supported on the arms F² by means of pins F¹⁴⁰. The arms F³ are pivotally supported on the rod F⁵ by means of pins F¹⁴¹, and the arms F² are pivotally supported on the base plate A¹ by means of pins F¹⁴². The arms F² are pivotally supported on the rod F⁵ by means of pins F¹⁴³, and the arms F³ are pivotally supported on the arms F² by means of pins F¹⁴⁴. The arms F³ are pivotally supported on the rod F⁵ by means of pins F¹⁴⁵, and the arms F² are pivotally supported on the base plate A¹ by means of pins F¹⁴⁶. The arms F² are pivotally supported on the rod F⁵ by means of pins F¹⁴⁷, and the arms F³ are pivotally supported on the arms F² by means of pins F¹⁴⁸. The arms F³ are pivotally supported on the rod F⁵ by means of pins F¹⁴⁹, and the arms F² are pivotally supported on the base plate A¹ by means of pins F¹⁵⁰. The arms F² are pivotally supported on the rod F⁵ by means of pins F¹⁵¹, and the arms F³ are pivotally supported on the arms F² by means of pins F¹⁵². The arms F³ are pivotally supported on the rod F⁵ by means of pins F¹⁵³, and the arms F² are pivotally supported on the base plate A¹ by means of pins F¹⁵⁴. The arms F² are pivotally supported on the rod F⁵ by means of pins F¹⁵⁵, and the arms F³ are pivotally supported on the arms F² by means of pins F¹⁵⁶. The arms F³ are pivotally supported on the rod F⁵ by means of pins F¹⁵⁷, and the arms F² are pivotally supported on the base plate A¹ by means of pins F¹⁵⁸. The arms F² are pivotally supported on the rod F⁵ by means of pins F¹⁵⁹, and the arms F³ are pivotally supported on the arms F² by means of pins F¹⁶⁰. The arms F³ are pivotally supported on the rod F⁵ by means of pins F¹⁶¹, and the arms F² are pivotally supported on the base plate A¹ by means of pins F¹⁶². The arms F² are pivotally supported on the rod F⁵ by means of pins F¹⁶³, and the arms F³ are pivotally supported on the arms F² by means of pins F¹⁶⁴. The arms F³ are pivotally supported on the rod F⁵ by means of pins F¹⁶⁵, and the arms F² are pivotally supported on the base plate A¹ by means of pins F¹⁶⁶. The arms F² are pivotally supported on the rod F⁵ by means of pins F¹⁶⁷, and the arms F³ are pivotally supported on the arms F² by means of pins F¹⁶⁸. The arms F³ are pivotally supported on the rod F⁵ by means of pins F¹⁶⁹, and the arms F² are pivotally supported on the base plate A¹ by means of pins F¹⁷⁰. The arms F² are pivotally supported on the rod F⁵ by means of pins F¹⁷¹, and the arms F³ are pivotally supported on the arms F² by means of pins F¹⁷². The arms F³ are pivotally supported on the rod F⁵ by means of pins F¹⁷³, and the arms F² are pivotally supported on the base plate A¹ by means of pins F¹⁷⁴. The arms F² are pivotally supported on the rod F⁵ by means of pins F¹⁷⁵, and the arms F³ are pivotally supported on the arms F² by means of pins F¹⁷⁶. The arms F³ are pivotally supported on the rod F⁵ by means of pins F¹⁷⁷, and the arms F² are pivotally supported on the base plate A¹ by means of pins F¹⁷⁸. The arms F² are pivotally supported on the rod F⁵ by means of pins F¹⁷⁹, and the arms F³ are pivotally supported on the arms F² by means of pins F¹⁸⁰. The arms F³ are pivotally supported on the rod F⁵ by means of pins F¹⁸¹, and the arms F² are pivotally supported on the base plate A¹ by means of pins F¹⁸². The arms F² are pivotally supported on the rod F⁵ by means of pins F¹⁸³, and the arms F³ are pivotally supported on the arms F² by means of pins F¹⁸⁴. The arms F³ are pivotally supported on the rod F⁵ by means of pins F¹⁸⁵, and the arms F² are pivotally supported on the base plate A¹ by means of pins F¹⁸⁶. The arms F² are pivotally supported on the rod F⁵ by means of pins F¹⁸⁷, and the arms F³ are pivotally supported on the arms F² by means of pins F¹⁸⁸. The arms F³ are pivotally supported on the rod F⁵ by means of pins F¹⁸⁹, and the arms F² are pivotally supported on the base plate A¹ by means of pins F¹⁹⁰. The arms F² are pivotally supported on the rod F⁵ by means of pins F¹⁹¹, and the arms F³ are pivotally supported on the arms F² by means of pins F¹⁹². The arms F³ are pivotally supported on the rod F⁵ by means of pins F¹⁹³, and the arms F² are pivotally supported on the base plate A¹ by means of pins F¹⁹⁴. The arms F² are pivotally supported on the rod F⁵ by means of pins F¹⁹⁵, and the arms F³ are pivotally supported on the arms F² by means of pins F¹⁹⁶. The arms F³ are pivotally supported on the rod F⁵ by means of pins F¹⁹⁷, and the arms F² are pivotally supported on the base plate A¹ by means of pins F¹⁹⁸. The arms F² are pivotally supported on the rod F⁵ by means of pins F¹⁹⁹, and the arms F³ are pivotally supported on the arms F² by means of pins F²⁰⁰. The arms F³ are pivotally supported on the rod F⁵ by means of pins F²⁰¹, and the arms F² are pivotally supported on the base plate A¹ by means of pins F²⁰². The arms F² are pivotally supported on the rod F⁵ by means of pins F²⁰³, and the arms F³ are pivotally supported on the arms F² by means of pins F²⁰⁴. The arms F³ are pivotally supported on the rod F⁵ by means of pins F²⁰⁵, and the arms F² are pivotally supported on the base plate A¹ by means of pins F²⁰⁶. The arms F² are pivotally supported on the rod F⁵ by means of pins F²⁰⁷, and the arms F³ are pivotally supported on the arms F² by means of pins F²⁰⁸. The arms F³ are pivotally supported on the rod F⁵ by means of pins F²⁰⁹, and the arms F² are pivotally supported on the base plate A¹ by means of pins F²¹⁰. The arms F² are pivotally supported on the rod F⁵ by means of pins F²¹¹, and the arms F³ are pivotally supported on the arms F² by means of pins F²¹². The arms F³ are pivotally supported on the rod F⁵ by means of pins F²¹³, and the arms F² are pivotally supported on the base plate A¹ by means of pins F²¹⁴. The arms F² are pivotally supported on the rod F⁵ by means of pins F²¹⁵, and the arms F³ are pivotally supported on the arms F² by means of pins F²¹⁶. The arms F³ are pivotally supported on the rod F⁵ by means of pins F²¹⁷, and the arms F² are pivotally supported on the base plate A¹ by means of pins F²¹⁸. The arms F² are pivotally supported on the rod F⁵ by means of pins F²¹⁹, and the arms F³ are pivotally supported on the arms F² by means of pins F²²⁰. The arms F³ are pivotally supported on the rod F⁵ by means of pins F²²¹, and the arms F² are pivotally supported on the base plate A¹ by means of pins F²²². The arms F² are pivotally supported on the rod F⁵ by means of pins F²²³, and the arms F³ are pivotally supported on the arms F² by means of pins F²²⁴. The arms F³ are pivotally supported on the rod F⁵ by means of pins F²²⁵, and the arms F² are pivotally supported on the base plate A¹ by means of pins F²²⁶. The arms F² are pivotally supported on the rod F⁵ by means of pins F²²⁷, and the arms F³ are pivotally supported on the arms F² by means of pins F²²⁸. The arms F³ are pivotally supported on the rod F⁵ by means of pins F²²⁹, and the arms F² are pivotally supported on the base plate A¹ by means of pins F²³⁰. The arms F² are pivotally supported on the rod F⁵ by means of pins F²³¹, and the arms F³ are pivotally supported on the arms F² by means of pins F²³². The arms F³ are pivotally supported on the rod F⁵ by means of pins F²³³, and the arms F² are pivotally supported on the base plate A¹ by means of pins F²³⁴. The arms F² are pivotally supported on the rod F⁵ by means of pins F²³⁵, and the arms F³ are pivotally supported on the arms F² by means of pins F²³⁶. The arms F³ are pivotally supported on the rod F⁵ by means of pins F²³⁷, and the arms F² are pivotally supported on the base plate A¹ by means of pins F²³⁸. The arms F² are pivotally supported on the rod F⁵ by means of pins F²³⁹, and the arms F³ are pivotally supported on the arms F² by means of pins F²⁴⁰. The arms F³ are pivotally supported on the rod F⁵ by means of pins F²⁴¹, and the arms F² are pivotally supported on the base plate A¹ by means of pins F²⁴². The arms F² are pivotally supported on the rod F⁵ by means of pins F²⁴³, and the arms F³ are pivotally supported on the arms F² by means of pins F²⁴⁴. The arms F³ are pivotally supported on the rod F⁵ by means of pins F²⁴⁵, and the arms F² are pivotally supported on the base plate A¹ by means of pins F²⁴⁶. The arms F² are pivotally supported on the rod F⁵ by means of pins F²⁴⁷, and the arms F³ are pivotally supported on the arms F² by means of pins F²⁴⁸. The arms F³ are pivotally supported on the rod F⁵ by means of pins F²⁴⁹, and the arms F² are pivotally supported on the base plate A¹ by means of pins F²⁵⁰. The arms F² are pivotally supported on the rod F⁵ by means of pins F²⁵¹, and the arms F³ are pivot

end of which is anchored at F^7 to the base of the machine. The force of the spring F^6 is oblique to the direction of the arms F^2 , and the arrangement is such that the upper ends of the arms F^3 as well as the ink well F^1 are normally urged upwardly toward the printing roller B . Rotatable within the ink well F^1 and partially below the surface of the ink is a roller F^8 which has surface contact with a distributing roller F^9 , of felt or similar material, said distributing roller in turn having surface contact with the printing roller B . The distributing roller F^9 is provided at its ends with trunnions F^{10} which are received in downwardly inclined slots F^{11} , in the upper ends of the swinging arms F^3 , and said arms F^3 are provided adjacent their lower ends with projections F^{12} , adapted to abut against adjusting screws F^{13} to limit the movements of said arms toward the roller B . A wiping roller F^{14} is also rotatably associated with the ink roller F^8 , it having trunnions F^{15} received in slots F^{16} in the end walls of the ink well F^1 , and said wiping roller engages the surface of the ink roller to relieve the same of superfluous ink before it rolls against the intermediate distributing roller F^9 . Thus a uniform amount of ink will at all times be applied to the die as the printing roller rotates, and there will be no feeding or distributing of ink when the printing roller is not rotating. To compensate for wear of the various parts, the adjusting screws F^{13} may be turned either in or out to determine the desired limit for the roller F^9 .

Integral with the base A^1 and forwardly of the ink well, is a slotted lug F^{17} in which is pivoted at F^{18} a latch F^{19} , said latch having a hook portion F^{20} adjacent its upper end for engagement with the upper edge of the ink well F^1 . A compression spring F^{21} normally forces said hook portion F^{20} toward the ink well, and when it is desired to temporarily discontinue the ink supply, (for example, when the roller F^9 has become saturated), the ink well is pressed downwardly about the pins F^4 to the position indicated by dotted lines in Fig. 5, in which position the latch holds it. In this condition, the printing roller B will continue to be inked by the distributing roller F^9 , due to the action of the springs F^6 on the arms F^3 indirectly through the ink well arms F^2 .

From the foregoing it will be clear that a novel inking mechanism has been provided for printing machines of this character, whereby the printing roller will be supplied with ink uniformly during the operation of the machine. The construction is extremely simple, capable of being economically produced, and the parts are easily accessible for inspection, adjustment or cleaning when necessary. Obviously the invention is susceptible of modification in the details of con-

struction, and arrangement of parts, and the right is herein reserved to make such changes as fall within the scope of the appended claims without departing from the spirit of the invention.

Having thus described my invention, what I claim is:

1. In a printing machine of the class described, the combination with a printing couple, of inking means including an ink well, an ink roller associated therewith, an ink distributing roller mutually engaging said ink roller and the printing member of the printing couple, swinging arms supporting the distributing roller for movement toward and away from the printing element, and an eccentric pivotal connection between said arms and the ink well.

2. In a printing machine of the class described, the combination with a printing couple, of inking means including an ink well, an ink roller associated therewith, an ink distributing roller mutually engaging said ink roller and the printing member of the printing couple, swinging arms supporting the distributing roller for movement toward and away from the printing element, and an eccentric pivotal connection between said arms and the ink well.

3. In a printing machine of the class described, the combination with a printing couple, of inking means including an ink well, an ink roller associated therewith, an ink distributing roller mutually engaging said ink roller and the printing member of the printing couple, swinging arms supporting the distributing roller for movement toward and away from the printing element, and an eccentric pivotal connection between said arms and the ink well, a latch for engaging the ink well to hold the ink roller, and means acting through the ink well support for maintaining the distributing roller in operative position with reference to the printing couple when the latch is in engagement with the ink well.

In testimony whereof, I have affixed my signature hereto.

RAYMOND F. JAHN.
